UNITED STATES PATENT OFFICE.

ARMITAGE S. C. FORBES AND HARRY R. P. FORBES, OF SOUTH PASADENA, CALIFORNIA.

DESIGN FOR A BELL-GUIDE-POST SOUVENIR.

46,278.

Specification for Design.

Patented Aug. 18, 1914.

Application filed April 22, 1914. Serial No. 833,815. Term of patent 14 years.

To all whom it may concern:

Be it known that we, ARMITAGE S. C. FORBES and HARRY R. P. FORBES, citizens of the United States, residing at South Pasadena, in the county of Los Angeles, State of California, have invented a new, original, and ornamental Design for a Bell-Guide-Post Souvenir, of which the following is a specification.

Figure 1 is a front elevation of a souvenir showing our new design. Fig. 2 is a side elevation as indicated by the arrow 2 in Fig. 1.

We claim—

The ornamental design for bell guide post souvenir as shown.

ARMITAGE S. C. FORBES.
HARRY R. P. FORBES.
